United States Patent Office.

WILLIAM VOLK, OF BUFFALO, NEW YORK.

Letters Patent No. 97,837, dated December 14, 1869.

IMPROVED VELOCIPED.

The Schedule referred to in these Letters Patent and making part of the same.

To all whom it may concern:

Be it known that I, WILLIAM VOLK, of Buffalo, Erie county, New York, now temporarily residing at Toronto, Canada, have invented a new and improved Velocipede; and I do hereby declare that the following is a full, clear, and exact description thereof, which will enable others skilled in the art to make and use the same, reference being had to the accompanying drawing, forming part of this specification, in which—

Figure 1 represents a vertical longitudinal section of my improved vélocipede.

Figure 2 is a plan or top view of the same.

Figure 3 is a detail side view of the connected axles. Similar letters of reference indicate corresponding parts.

This invention relates to a new three-wheeled vélocipède, which is so arranged that the driving-wheels, although mounted on separate axles, will make equal numbers of revolutions as long as the machine is to be kept in a straight direction, while they can be disconnected when the device is to be turned in a circle.

The invention consists in the application of a toothed wheel, which meshes into pinions on the separated axles, to connect the same, and which is hung on a pivoted lever, so that it can be readily thrown out of gear when the axles are to be disconnected.

The invention also consists in the general combination of parts for imparting motion to the vehicle.

A, in the drawing, represents the frame of my improved velocipede.

B is the driver's seat supported thereon.

C C are the front driving-wheels, mounted on separate axles D D, that have their bearings in the frame A in front of the seat.

The axles D D are in line with each other, and their inner ends are brought close together within the inner supporting-box α of the frame.

Pinions b b are mounted upon the contiguous inner ends of the axles D.

E is a lever, pivoted to the frame A under the seat, and extending over the contiguous ends of the axles D.

A pinion, c , is hung on the end of the lever E, and is, by a spring, d , held in contact with both pinions b which it connects.

When the two axles D are revolved by means of foot-levers F, or hand-levers G, or both, their motion will be equalized by the pinion c , which will cause both wheels to make equal revolutions.

When the velocipede is to be turned on a curve, the lever E is, at its rear end, depressed by the foot of the driver, to raise the pinion c out of gear. Then one wheel, C, can be kept stationary, while the other revolves.

The rear end of the frame A is supported on a caster-wheel, H, as shown.

The hand-levers G are pivoted to the frame, and connect with rods e , which embrace eccentrics f of the axles, as shown.

The foot-levers may be connected directly with cranks g of the axles:

Having thus described my invention,

What I claim as new, and desire to secure by Letters Patent, is—

1. The lever E, carrying the pinion c , and acted upon by the spring d , when arranged to connect the pinions b on the ends of the axles D, substantially as herein shown and described, for the purpose specified.

2. The combination of the separate driving-axles D D, which carry the pinions b , eccentrics f , and cranks g , with the lever E, pinions c , levers F and G, and rods e , all arranged and operating substantially as herein shown and described.
